Specification of Letters Patent.

Patented Oct. 1, 1918.

Application filed November 24, 1915. Serial No. 63,206.

To all whom it may concern:

Be it known that I, WILLIAM F. A. BUEHNER, residing at Newark, in the county of Essex and State of New Jersey, have invented certain new and useful Improvements in Mufflers, of which the following is a specification.

This invention relates to a muffler for deadening the sound of an internal combustion engine or the like.

The object of the invention is to provide a simple, cheap, efficient and easily cleanable muffler.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention:

Figure 1 is a transverse sectional view of a muffler constructed in accordance with the provisions of this invention.

Fig. 2 is an end elevational view of the structure shown in Fig. 1; and

Fig. 3 is a top plan view of the muffler, showing the same in position upon a multi-cylinder engine, said view being upon a reduced scale.

Although this invention is shown in the drawings as being adapted for use upon a two-cylinder engine, it will be obvious that it may be used in connection with a single cylinder or in connection with engines having cylinders in multiples of two.

Referring to the structure illustrated in the drawing, the reference character L indicates a two-cylinder engine. The cylinders, as 1 and 2, of this engine are shown in opposing position, but it will be obvious that this disposition of the cylinder has no bearing upon the points of the invention.

A casing G is arranged adjacent the cylinder having an opening 3 communicating with the exhaust port of the cylinder 1. The casing is formed to provide a passage-way 4, a passage-way 5 at an angle to the passage-way 4, a passage-way 6 lapping back upon the

passage-way 5 and opening outwardly into an extension member H. The extension H is provided with a partition 7 therein defining a passage-way 8 communicating with the passage-way 6 and a passage-way 9 lapping upon the passage-way 8. One wall of the extension H defining the passage-way 9 is perforated, as at 10, for the escape of the spent gases.

As the drawing indicates the invention is adapted for use upon a two-cylinder engine, the casing G is made double and an extra extension is provided, as illustrated, to care for the gases from the cylinder 2. An opening 3 is thus provided into the cylinder 2, and passage-ways 4, 5, 6, 8 and 9 are all duplicated for the escape of the gases from the cylinder 2.

In order to simplify and cheapen the construction the casing G is made with a single division wall 11 between its two sets of passage-ways. The exhausting gases from the two cylinders strike this division wall alternately from opposite sides and continue therewith to their respective points of release.

The casing G is preferably made as a single integral casting having flanges 12 thereon by means of which it may be attached to the engine cylinders. The passage-ways 5 and 6 are defined by partition walls or baffle plates 13 provided therein as shown.

The extensions H preferably each comprise a short section of metallic tubing cut to a proper length and having their inner ends abutting relative opposite surface portions of the casing G. Portions of the walls of the casing are removed, as at 14, to provide unobstructed passage outwardly from the passage-ways 6 into the extensions. The walls of the casing are projected outwardly into the extensions H so as to provide the partition 7. The outer end of the extensions are closed by cap pieces 15. A bolt 16 extends between the cap pieces 15, through suitable apertures formed in the casing, and serves to clamp the extensions firmly and rigidly in position upon the casing.

By the above means a separate and distinct exhaust passage is provided for the 105 exhausting products of combustion from each cylinder of the engine and a common wall is provided constituting a buffer against the opposite surfaces of which the exhaust products of combustion from the cylinders 110

strike. Ample, and sufficiently tortuous, passage-way is provided for effectually absorbing the force and deadening the noise of the outgoing gases.

5 As many changes could be made in this construction without departing from the scope of the following claims, it is intended that all matter contained in the above description or shown in the accompanying 10 drawing shall be interpreted as illustrative only and not in a limiting sense.

Having thus described my invention what I claim as new and desire to secure by Letters Patent is:

15 1. A muffler comprising a casing defining a passage-way and having an opening through the wall thereof at the end of the passage-way, a separately formed hollow extension communicating with said opening 20 for providing a continuation of said passage-way, the outer end of said separately formed hollow extension being closed, and a partition in said extension extending longitudinally thereof from the wall of the casing 25 to adjacent the outer end of the extension and at one side of the opening between said casing and said extension for defining a passage-way from the opening in the casing along one side of the partition to the 30 outer end of the extension and backwardly along the opposite side of the partition, and said extension having openings leading to the atmosphere.

2. A muffler comprising a casing defining 35 a passage-way and having an opening through the wall thereof at the end of the passage-way, a separately formed hollow extension communicating with said opening for providing a continuation of said passage-way, the outer end of said separately formed hollow extension being closed, and a partition in said extension extending longitudinally thereof from the wall of the casing 40 to adjacent the outer end of the extension and at one side of the opening between said casing and said extension for defining a passage-way from the opening in the casing along one side of the partition to the 45 outer end of the extension and backwardly along the opposite side of the partition, and that wall of the extension facing said opposite side of the partition being perforated.

3. A muffler comprising a casing defining a passage-way and having an opening through the wall thereof at the end of the 55 passage-way, a separately formed hollow extension communicating with said opening for providing a continuation of said passage-way, the outer end of said separately formed hollow extension being closed, and a projection formed upon the wall of the casing at one side of the opening therethrough projecting into said extension so as to define a partition in the extension terminating short of the outer end of said extension, and said extension having openings leading to the atmosphere.

4. A muffler comprising a casing having a pair of intake openings thereinto for the entrance of products of combustion, said casing having a pair of other openings through the wall thereof for the escape of said products of combustion, and means dividing the casing so as to form independent passage-ways between said inlet and escape opening 75 respectively, said means comprising a partition wall arranged in said casing so as to constitute a buffer common to the products of combustion passing through both said passage-ways.

5. A muffler comprising a casing defining a passage-way and having an opening through the wall thereof at the end of the passage-way, a separately formed hollow cylindrical extension communicating with the opening for providing a continuation of said passage-way, a closure member closing the outer end of the extension, a member formed integrally with the casing projecting longitudinally into said extension to 90 form a longitudinal partition within the extension at one side of said opening terminating short of the closure member, one wall of the extension being perforated, and a clamp bolt extending from the casing through the 95 extension and into engagement with the closure member to retain all said parts in operative engagement.

In testimony whereof I affix my signature in the presence of two witnesses.

WILLIAM F. A. BUEHNER.
